Primary Examiner — Keli L Hill*Assistant Examiner* — Karra S Johnson(74) *Attorney, Agent, or Firm* — Chris J. Katopis(57) **CLAIM**

The ornamental design for an animal paw-themed earbud, as shown and described.

DESCRIPTION

FIG. 1 is a front perspective view of an animal paw-themed earbud, showing the new design;

FIG. 2 is a front view thereof;

FIG. 3 is a back view thereof;

FIG. 4 is a side view thereof;

FIG. 5 is a top view thereof; and,

FIG. 6 is a bottom view thereof.

The broken lines shown are included for the purpose of illustrating portions of the animal paw-themed earbud that form no part of the claim.

1 Claim, 6 Drawing Sheets(56)
